(57) **CLAIM**
The ornamental design for a laptop computer, as shown and
described.

DESCRIPTION

FIG. 1 is a bottom, front, and left side perspective view of
a laptop computer showing my new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.
The broken lines depict portions of the laptop computer that
form no part of the claimed design.

1 Claim, 7 Drawing Sheets
